UNITED STATES PATENT OFFICE

2,395,830

MEANS FOR FORMING SHEET METAL

Howard M. Jager, Oceanside, and Edouard Schenk, New York, N. Y., assignors to Republic Aviation Corporation, a corporation of Delaware

Application November 3, 1942, Serial No. 464,356

7 Claims. (Cl. 153—48)

The present invention has to do with forming sheet-metal into various hollow shapes, and this application is similar in some respects to the patent to Howard M. Jager, No. 2,378,482, dated June 19, 1945.

Although the present invention, like that of said patent, also relates generally to a means for forming sheet metal by applying a novel clamping action to the sheet while stretch-forming the sheet, the present invention is particularly concerned with forming flat sheets of metal into hollow bodies that are considerably thinner, or of lesser cross-section, than those that could be dealt with in the machine of said patent, and in addition, having taper at each end, instead of at only one end; that is to say, instead of being of constricted shape at only one edge or end, they are constricted at both edges or ends.

More specifically, this invention has especial reference to forming such relatively shallow, flat, extensive, hollow, curved metal bodies as aircraft fins, rudders, flaps, ailerons, elevators, stabilizers and the like. In forming such articles by employing the general principles of said application and said invention, it is contemplated by the present invention to apply the stretching-force in a different manner and position; to provide a differently-acting clamping force, located in a different position; and to provide different means for permitting insertion of the work-sheet in a different manner in the machine, from the modes and means disclosed in said application and it is one of the objects of this invention to make these provisions.

The other objects of, and results achieved by, the invention will become manifest as this disclosure proceeds.

One form of embodiment of the inventive concepts is shown in the accompanying drawing, and described hereinafter, by way of example, only; and it is to be understood that the invention is limited in its embodiments only by the scope of the subjoined claims.

In the drawing:

Figure 1 is a fragmentary side elevation of a sheet-metal forming machine embodying the present invention;

Figure 2 is an enlarged end-view, partly in section, along line 2—2 of Figure 1, and

Figure 3 is an enlarged section along line 3—3 of Figure 1, showing the parts in another position.

The stretching machine is shown as applied to form the "skin" of the leading or hinge edge of an aircraft rudder and includes a stationary lower

form block 22, in the lower portion of which is formed a central recess defining two legs 22' extending longitudinally of the block. This block 22 is provided with two opposed end-ears 23 resting in corresponding self-aligning seats 24 formed in a pair of H-shaped uprights 24 forming part of a support or operating table 25, 26.

Before it is processed therein, the metal sheet 20 to be formed is bent in a compound bend along its opposed longitudinal edges in such manner as to form two U-channelled retaining borders. It is then fitted over an upper movable form-block 21 of the machine, which block rests on the stationary block 22.

15 The single clamp used to anchor the longitudinal channelled edges of the sheet 20 around legs 22' during the stretching operation is an improvement upon the clamp shown in the above mentioned Jager application, and, like the former, 20 includes a gang nut or wedge 10, and a lower jaw 11 suspended from said wedge by means of a plurality of tightening devices, but, in the present invention, the upper jaw of the clamp is formed by the legs 22' of the block 22. Both 25 slanting sides of the wedge 10, instead of but one side, cooperate with the inner faces of said legs 22' to clamp the upturned wings of the U-channels formed along the edges of the work sheet 20. In the present invention also, there are 30 tightening devices, but herein take the form of studs 12, having opposed heads 13, 14. Through holes in the lower heads 14 passes a longitudinal shaft 15 made in two parts, each part carrying a plurality of cams or eccentrics 16, fixed on the 35 shaft 15 by means of keys 17. The two halves of the shaft 15 may be operated simultaneously by means of a pair of opposed handles 18, slidably mounted across hubs 18 fixed on the opposed outer ends of the shaft parts 15.

The upper movable block 21 can be spread apart from the lower block 22, with the sheet of metal engaged around the top, by means of a hydraulic jack schematically shown as a power unit fitting within a corresponding elongated hole formed half in the block 21 and half in the block 22. This power unit comprises an elongated hydraulic chamber 28 preferably of U-section housed in the fixed block 22 and an elongated plunger 29, the head of which is similarly housed in the movable block 21. An operating fluid 30, preferably oil, is admitted into the chamber 28 through conduits (not shown).

Each clamping assembly, including elements 10—19, rests freely on the table 25, 26 when the machine is at rest (as in Figure 1) and is car-

ried by the block 22 when the machine is in operation (as in Figure 3).

In order to facilitate the insertion of the channelled edges of the work sheet 20 around the legs 22', the table 25, 26 is extended considerably beyond the two ears 23 and the two clamping assemblies 10 to 19, can be slid in opposite directions along said extensions by means of cooperating slanting guiding surfaces 27, 31 so as to clear the two lateral entrances for said channelled edges provided between each of the legs 22' and the corresponding longeron 25 of the table 25, 26.

Normally, there is no fluid in the chamber 28, and the movable block 21 rests upon the fixed block 22. When it is desired to put a work sheet 20 in position on the form 21, 22, the two clamping assemblies, 10 to 19, are first withdrawn from under the block 22 and one U-channel only of the work sheet 20 is engaged upwardly over one leg 22' of the block 22, the sheet being held vertically and then fitted over the top of the block 21, and the opposite U-channel is then snapped into the other leg 22' of the block 22. The slides 10 to 19 are then slid back, springs 32 facilitating the entrance of the wedges 10 into the recess of the block 22 between the opposite inner wings of the two U-channels and the eccentrics 16 are simultaneously turned the desired angle so as to wedge the gang nut 10 against said wings and press the lower jaw 11 up against the bottom of the U-channels.

Thus anchored to the fixed part 22 of the machine, the work sheet 20 can be stretched beyond its elastic limit and permanently deformed into the desired shape, by applying pressure fluid, thus being given a permanent deformation without having to carefully control the pressure applied, as the upturned edges of the sheet 20 will merely slip out of the clamp if this pressure reaches a value above the ultimate tensile strength of said sheet, instead of excessive stretching forces tearing the sheet, as was usually heretofore the case.

By having interchangeable blocks 21, 22 of varying shapes and lengths, it is possible to use the machine for forming a great variety of shallow skin sections of aircraft structures, and by interposing shims 33 between the upper heads 13 of the studs 12 and the wedges 10, it becomes possible to form sheets of different gage without having to make any change or adjustment in the machine. It is to be noted, that, as there is no vibration in the machine during its operation, the clamping assemblies 10 to 19 can be, and are, self-locking.

After the sheet 20 is thus stretched to the desired extent and formed, the hydraulic pressure is released and the two opposed handles 19 are turned in order to loosen the clamp. The block 21 then falls from the operative position shown in Figure 3 into the inactive position shown in Figure 2, while the plates 11 fall on the table 25, 26, and the wedges 10 are lifted by the action of the springs 32, thereby freeing the sheet 20, which can then be easily removed endwise from the gripping jaws 10, 11 and 22'.

The retaining channels of the skin section thus obtained may, after this removal, either be trimmed away, or be retained as reinforced edges, which may later on, when assembled with the usual transversal ribs and a longitudinal web riveted to the bottom of these channels—form the spar of an aircraft or other structure, such as of a fin, flap or the like.

Although, in the disclosed embodiments the clamping pressure is manually applied and is independent of the stretching or drawing mechanism, it is to be understood that this clamping pressure can be applied by any other suitable means.

It will be noted that the stretching machine is an internally expanding one and has a single, central clamp adapted to associate the two lower longitudinal edges of the sheet closely adjacent each other in juxtaposition in such manner as to form thereby, a single continuous force-absorbing structure thereat, the forming-zone consisting of two internally separable blocks in juxtaposition with each other, over which the sheet-metal is stretched by internal expansion. The work member is thus arranged to substantially completely envelop the entire stretching zone or forming dies, in which zone the tensile force is applied by separating the dies by internal expansion. The expansion is achieved by automatic power means and the blocks form a compact "form-unit" which unit may be varied in size, at will, by interchanging with blocks of other sizes. In operation, the work itself forms an oil seal at the increasing gap between the members 21 and 22. Insertion of fresh work sheets is also facilitated and rendered easier than heretofore, by these means, and yet the original advantages of the foregoing machine are retained withal.

Having thus disclosed the inventive concepts and one embodiment thereof, what is claimed is:

1. In a machine of the type described; a base; a form-group mounted thereon, the lower part 35 of the form having a recess therein; a wedge-member mounted in said recess; said wedge having spaced apertures therein; a plate mounted on said base adjacent said recess and having corresponding apertures therein; a plurality of double-acting fastening members mounted to extend thru said apertures to join the wedge and plate; a shaft rotatably mounted in the lower ends of said fastening members; a plurality of eccentrics mounted on said shaft; and means for rotating said shaft.
2. In a machine for stretching sheet metal into hollow forms the combination with a pair of separable superposed die members to be enveloped by a work sheet, one of said members having a groove in its under face with upwardly divergent walls, of a movable wedge member coextensive with said groove having its sides convergent to lie substantially parallel to the walls of said groove regardless of its position within the groove, an external clamping jaw opposed and parallel to the grooved face aforesaid, and a connection between said wedge member and said external jaw whereby they may be moved simultaneously toward one another to engage the edges of the work sheet between the sides of the wedge and the walls of the groove at the same time and clamp portions of the work sheet adjacent its engaged edges between the external jaw and the grooved die face upon each side of said groove.
3. In a machine for stretching sheet metal into hollow forms the combination with a pair of separable superposed die members to be enveloped by a work sheet the lower of said members being stationary and having a relatively flat under surface with a groove centrally positioned therein for receiving the opposed edges of the work sheet, the walls whereof diverge upwardly, of a wedge member coextensive with and movable vertically in said groove having its sides convergent to rest substantially parallel to the walls

of said groove regardless of its position within the groove, an external clamping jaw opposed and parallel to the under grooved face aforesaid, and a connection between said wedge member and said external jaw whereby they may be moved simultaneously toward one another to clamp the edges of a work sheet enveloping both die members between the sides of the wedge and the walls of the groove and those portions of the work sheet adjacent to the clamped edges between the external jaw and said grooved under face upon each side of said groove.

4. In a machine for stretching sheet metal into hollow forms, the combination with a pair of superposed separable die members the work faces of which converge in opposite directions, power means for moving said die members in opposite directions against a work sheet entirely enveloping and resting flush against the work faces thereof, the lower of said die members having a relatively flat outer surface provided with a central groove the walls of which diverge upwardly, a wedge member movably positioned within and coextensive with said groove the sides of which converge to lie always parallel to the walls of the groove, an external clamping jaw parallel to the aforesaid flat outer surface, connections between said wedge member and said external jaw permitting relative movement thereof, and means to move said jaw and said wedge member simultaneously toward each other whereby the extreme edge portions of a work sheet enveloping said die members are engaged between the sides of the wedge and the walls of the groove while those portions of the work sheet adjacent the extreme edge portions are independently clamped between the movable jaw and the flat outer surface aforesaid upon each side of the groove thereof.

5. In a machine for stretching sheet metal into hollow forms the combination with a pair of superposed separable die members the work faces of which converge in opposite directions, power means for moving said die members in opposite directions against a work sheet entirely enveloping and resting flush against the work faces

of said die members, the lower of said die members having a relatively flat under surface for cooperation with the opposed edge portions of a work sheet enveloping said members and provided with a central substantially coextensive groove the walls of which diverge upwardly, a wedge member movably positioned within said groove and coextensive therewith having its walls convergent to lie always parallel to the walls of the groove, an external clamping jaw parallel to the flat surface aforesaid, connections between said wedge member and said external jaw, springs interposed between said wedge member and said external jaw tending to separate them, and means for moving said jaw and wedge one toward the other against the action of said spring whereby the extreme edge portions of the work sheet are engaged between the sides of the wedge and the walls of the groove while those portions of the work sheet adjoining said extreme edge portions are independently clamped between the movable jaw and the flat surface aforesaid upon each side of its groove.

6. In a machine for stretching sheet metal into hollow forms, the combination with a pair of separable die members, the work faces of said die members converging in opposite directions and one of said members having a base of less width than the greatest width of either of said die members, and a single means associated with said base for clampingly engaging the opposed edge portions of a work sheet completely enveloping said die members with its edge portions resting flush against said base.

7. In a machine for forming sheet metal the combination with aligned die members separable to stretch form a work sheet, one of said die members having an outer base surface, of means associated and positioned medially with respect to said base surface to clampingly engage the edge portions of a work sheet enveloping and resting flush against the surfaces of both of said members with its edge portions lying against said base surface.
